UNITED STATES PATENT OFFICE

JOHN ELLIS, OF PHILADELPHIA, PENNSYLVANIA, ASSIGNOR TO ELLIS IMPORTING COMPANY, A FIRM COMPOSED OF JOHN ELLIS, SAMUEL ELLIS, AND ISRAEL ELLIS

DESIGN FOR A STORE FRONT

Application filed July 3, 1929. Serial No. 31,934. Term of patent 14 years.

To all whom it may concern:

Be it known, that I, JOHN ELLIS, a citizen of the United States, residing at 6814 North Broad Street, Philadelphia, county of Philadelphia, State of Pennsylvania, have invented a new, original, and ornamental Design for Store Front, of which the following is a specification, reference being had to the accompanying drawings, forming part thereof.

I claim:—

The ornamental design for a store front as shown.

JOHN ELLIS.
